UNITED STATES PATENT OFFICE.

ELIAS LEWIS, OF DENVER, COLORADO.

DEVICE FOR SHARPENING ROCK-DRILLS.

No. 866,041.

Specification of Letters Patent.

Application filed June 9, 1903. Serial No. 160,716.

Patented Sept. 17, 1907.

To all whom it may concern:

Be it known that I, ELIAS LEWIS, a citizen of the United States, residing at Denver, in the county of Denver and State of Colorado, have invented a new and 5 useful Device for Sharpening Rock-Drills, of which the following is a specification.

My invention relates to improvements in machines for sharpening rock-drills and more particularly for the class of drills having four cutting edges, and being 10 cross-shaped in section throughout their entire extent.

The object of my invention is, to provide a machine for sharpening rock-drills which, being most simple in construction, can be manufactured at a small cost, and which, in one movement, will form and sharpen the 15 cutting edges of a drill, and on this account, will save time and labor, while producing satisfactory results. I attain these objects by the mechanism illustrated in the accompanying drawings, in which

Figure 1 represents a plan view of my device, the upper lever being broken away. Fig. 2 is a longitudinal section taken along the line 2—2 Fig. 1. Fig. 3, is an enlarged sectional view of the cylinder valve. Fig. 4, is an enlarged view, partly in section of a modified form of connecting-rod. Fig. 5, is a section taken along line 25 5—5 Fig. 2, drawn to a reduced scale. Fig. 6, is a cross-section taken along the line 6—6 Fig. 2, showing the closed position of the dies. Fig. 7, is a reduced cross-section taken along line 7—7 Fig. 2, looking in the direction of the arrow, (connecting-rod, cylinder etc., omitted). Fig. 8, is an enlarged section taken along the line 8—8 Fig. 2. Fig. 9, is an enlarged perspective view of the lower extremity, of the short arm of one of the levers showing die in place. Fig. 10, is an enlarged perspective view of the cutting end of a drill after having been 30 cut and formed by my machine. Fig. 11, is an enlarged perspective view of the forked portion of the guiding standards.

Similar reference characters refer to similar parts throughout the various views.

40 My device consists of a base 5, preferably made of iron, and on which are erected two rectangular frames 6 and 7 parallel to each other and secured together by means of braces 8. Four bent-levers, 9 are fulcrumed in boxes 10, secured on the inside of frame 6, the points 45 of fulcrum of the four levers being located at equal distances from a point A, while the lines of fulcrum are at right angles to each other. Bent levers 9, when in place, are at right angles to each other, the extremities of the short arms 9^a being directed towards each other and towards the center point A, while the long arms 9^b extend backward through and beyond frame 7. The extremities 9^c, of the short arms 9^a, are provided with dove-tailed grooves 9^d, into which are placed the correspondingly shaped ends 30^a, of dies 30.

45 The opposite or working ends 30^b, of dies 30, projecting below the ends of the short arms 9^a, are provided

with two cutting edges 30^c, formed at right angles to each other, the apexes 30^d, of the angles pointing towards the center, point A. The sides of the cutting edges 30^c, are beveled, the angle between them varying 60 for different kinds of drills. These sides are the swages by which the cutting edges of the drill are formed.

The lower edges of the arms 9^a, extending from the dies to the front, are sloped outwardly to allow the unobstructed introduction of the drill rod between the 65 dies, and having bevel-sided edges placed at right angles to each other and adapted to engage the wings of the drill-rod inserted between the dies, when the thickness of the steel is such that the lower edges of the short arms 9^a of levers 9 will engage the drill-rod 70 prior to the meeting of the apexes of the four dies in the central point A. The pressure exerted by the bevel-sided edges of the arms 9^a on the wings of the drill-rod will cause the metal of which they are composed, to be displaced, in consequence of which, the 75 wings will be spread outwardly, thus producing the flaring extremity shown in Fig. 10, and which, owing to the increased resistance in heavy drill-rods, can not be produced by the swaging edges of the dies.

The dies are held in place in the slots 9^d, by pins 11, 80 which are driven into the holes formed by correspondingly located semi-circular grooves in the upper surface of the dove-tailed end 30^a, of the dies and the adjoining surface of the grooves 9^d.

The location of the dies in the extremities of the 85 short arms 9^a, is such that, when the ends of the long arms 9^b, are made to diverge, and the extremities of the arms 9^a, in consequence converge, the apexes 30^d, of the four dies, 30, will meet in the before mentioned point A, while their cutting edges 30^c, will meet in two 90 straight lines, crossing each other at right angles at the point of meeting of the apexes.

The diverging of the ends of the long arms 9^b, may be accomplished in various ways, either by hand power, by the application of steam, compressed air or 95 hydraulic power, or by other suitable means. The appliance for accomplishing the purpose, as illustrated in my drawings, is designed to be operated by either steam or compressed air. A horizontal hollow cylinder 12, mounted on a suitable base, is located beyond 100 frame 7, its axial center line being in line with the heretofore described point A, in which the apexes 30^d, meet. A piston 14, with piston rod 15, has a reciprocating movement in said cylinder, the ends of the latter being closed by cylinder covers 12^a, and 12^b, the former 105 of which has been provided with a packing box 12^c, through which the piston rod passes. The end of piston rod 15, projecting outside the cylinder, is connected with a cross head 16, preferably rectangular in shape, which has a reciprocating movement in angular guide 110 ways 17, which are erected on the cylinder frame and secured together by straps 17^a. Cross head 16 is pro-

vided on its 4 sides with lugs 18, to which are pivoted connecting rods 19, by means of pins 18^a, passing through holes in said lugs and corresponding holes in the ends of rods 19, the opposite ends of the connecting rods 5 being pivotally secured to the extremities of the long arms 9^b, of levers 9. The connecting rods being thus applied, form toggle joints, of which the cross head constitutes the knuckle, and by means of which the long arms are forced outward when the piston is driven 10 forward, and vice versa. A three-way valve 20, at the rear end of the cylinder connects the interior of cylinder 12, with the steam or air supply during the forward and with the atmosphere during the backward stroke of the piston by manipulation of the valve handle 20^a.

15 To insure the lateral position of the long arms 9^b, of levers 9, during their movement, I have provided frame 7, on its inside with 4 rectangular frames 21, two of 7, the sides of which are secured to the sides of the frame 7, while their opposite sides form guide ways 22, in 20 which the arms 9^b, travel.

As it is essential in the operation of my device that the cutting edges 30^c, and apexes 30^d, of dies 30, meet when forming the cutting edges of the drills, it is of the greatest advantage to the operator to have means for 25 adjusting the downward movement of the arms 9^a, when through long and constant use or for any other reasons, the working ends of the dies, extending beyond the lower ends of arms 9^a, have become too short to properly cut and form the ends of the drill rods. This 30 adjustment may be accomplished by increasing the length of the piston-stroke, but, if for some reason this should not be practical, use may be made of the adjustable connecting rods, illustrated in Fig. 4, and which consist of two short rods 19^a, the opposite extremities 35 19^a, of which are provided with eyes by means of which they may be pivotally connected to the extremities of arms 9^b, or to the lugs 18, of cross-head 16, while their adjacent extremities are provided with right and left hand screw-threads and connected by means of a turn-40 buckle 23.

As it is important that the drill rod should be fed straight in between the cutting edges of dies 30, I have provided my machine with one or more adjustable, forked guide, standards 24, consisting of a threaded rod 45 24^b, secured to an extension of the base 5, and a second rod 24^b, the upper extremity 24^c, of which is forked, while its lower extremity is threaded and connected to the threaded extremity of rod 24^a, by means of a turn-buckle 25, which allows the lengthening and shortening 50 of the standards to suit circumstances. The standards being in line with the center of the machine, will afford a rest for and guide the drill rod, the end of which it is desired to sharpen. Although but one of the standards is shown in the drawings, it will in many cases be ad-55 visable to use two or even more, depending on the length of the drill rod used.

One of the levers 9, is provided at a point back of the die 30, with an inwardly extending projection 26, either integral with the lever or secured thereto by 60 bolts or other means. The extension 26, is provided at its free end with a threaded aperture for the reception of a screw-bolt 27, having an integral head 27^a, at one end, while it may be provided with a swiveled head or plate 27^b, at its opposite end nearest the die 30. When 65 the drill-rod is thrust in between dies 30, the swiveled

head 27^a, will form an abutment preventing the further inward movement of the drill-rod, and by turning the bolt, the head 27^a, may be brought nearer to or farther away from the dies, as the case may demand.

Having thus described the mechanical construction 70 of my invention, its operation is as follows: The piston, connecting rods and levers, being in the position illustrated in broken lines in Fig. 2, the drill rod is placed in the forks 24^c of the standards 24, and thrust in between the ends of the arms 9^b, of levers 9, until arrested 75 by bolt 27. The drill rod used, is fluted, (see Fig. 10) its wings being at right angles to each other, making the rod cross-shaped in section. The position of the rod in between the dies is illustrated in Fig. 5, in broken lines, 80 the wings extending in between the adjacent cutting edges of the dies, while the points of the dies are located in the fluted portions of the rod. The length of the cutting edges 30^c of the dies should be equal to or exceed the distance from the center of the drill-rod to the outer edge of the wings and the angle between the bevelled sides of the cutting edges may be varied, according to the drills, to be sharpened, some ores requiring blunter cutting edges on the drills than others. When the drill, which has been previously brought to a red-hot state, is put in the machine, as described, the position of the valve 20 is reversed and air or steam let in behind the piston, driving same forward, thereby, by medium of the connecting rods, diverging the ends of the long arms of the levers and forcing the dies together. The cutting edges 30^c, on coming together, 95 will separate the portion of the rod between them and the end of bolt 27, from the main piece, while the beveled swaging surfaces of the sides of the cutting edges will impart to the wings of the rod the required V-shaped cutting edges. The metal displaced by the 100 swaging, being forced outward, will increase the width of the wings at that end of the rod, thus producing the flaring end illustrated in Fig. 10.

The cutting edges 30^c, of the dies 30, are shown as beveled on both sides, although only one side takes 105 active part in the forming of the drill edge.

The double edge, as illustrated, allows the reversing of the dies, although not essential, and the cutting edges of the dies may be chisel-shaped if so desired.

Having thus described my invention, what I claim is: 110

1. In a device for sharpening rock-drills, the combination with a suitable base of a frame erected thereon, four levers fulcrumed in said frame, dies secured to the converging extremities of the short arms of said levers, a cylinder located on said base, a piston having a reciprocating movement in said cylinder, means for admitting and exhausting air or steam in and from said cylinder, a piston rod secured to said piston, guide ways erected on said base, a cross head having a reciprocating movement in said guide ways, being connected with said piston-rod, connecting rods pivotally connected with said cross head and with the extremities of the long arms of said levers, and suitable means for adjusting the length of said connecting rods, substantially as described. 115

2. In a device for sharpening rock-drills, the combination with a suitable base of two rectangular frames erected thereon, braces connecting said frames, four levers fulcrumed in one of said frames, sharpening and forming dies secured to the converging short arms of said levers, their long arms extending through and beyond said second frame, means in said frame for guiding said arms, means for guiding and supporting a drill rod placed between said dies, means for limiting the inward movement of said drill rod, a steam or air cylinder, having a reciprocating 120 13

5 piston located on said base, a cross head connected with said piston and moving in suitable guide ways, lugs on said cross head, connecting rods pivoted to said lugs, while their other ends are pivoted to the extremities of said long arms, and suitable means for lengthening or shortening said connecting rods, substantially as described.

3. In combination with a plurality of pivotally supported levers arranged opposite each other, dies carried by the said levers, each having two beveled-sided cutting edges placed at right angles to each other, said dies being arranged to meet at a central point and separate the metal and means at the side of the levers and dies to support the rod being operated on, the said dies in closing upon the rod moving away from said supporting means, substantially as described.

4. In combination with the swinging levers carrying the dies, a stop carried by one of the swinging levers and moving therewith away from the point at which the dies come together, substantially as described.

20 5. In combination with the swinging levers carrying the dies, a stop adjustably supported by one of the levers and movable therewith away from the point at which the work is done when the dies come together, substantially as described.

25 6. A device of the class named, comprising in combination, a plurality of pivotally supported levers, arranged in pairs, the levers of each pair being opposite each other,

means on said levers adapted to spread the metal, dies carried by said levers, said dies being arranged to separate the metal transversely and meet at a central point.

30

7. A device of the class named, comprising in combination, a plurality of pivotally supported levers, arranged in pairs, the levers of each pair being opposite each other and having edges adapted to spread the metal and equidistantly located from a central line, dies carried by said levers at a point in said edges remote from their outer extremities, said dies being arranged to separate the metal transversely and meet at a point within said central line.

35

8. A device of the class named, comprising in combination, a plurality of pivotally supported levers, arranged in pairs, the levers of each pair being opposite each other and having bevel-sided edges placed at right angles to each other equidistantly from a central line, dies carried by said levers at a point in said edges, each having two bevel-sided cutting edges, placed at right angles to each other, said dies being arranged to separate the metal transversely and to meet at a point in said central line.

40

In testimony whereof, I have signed my name to this specification in the presence of two subscribing witnesses.

ELIAS LEWIS.
